STORE FIXTURE

Herbert Malott, Detroit, Mich., assignor to Detroit Show Case Company, Detroit, Mich., a corporation of Michigan

Application June 12, 1935, Serial No. 26,121

5 Claims. (Cl. 312—138)

This invention relates to store fixtures and the object of the invention is to provide an arrangement whereby a store fixture may be built up in a series of sections to which different sections 5 may be added or taken away as desired.

Another object of the invention is to provide a store fixture of the cabinet type having a series of sections connected together by a molding to which different parts may be anchored.

10 Another object of the invention is to provide a store fixture provided with sliding doors and having ways for the doors anchored to the molding, the arrangement being such that the doors may be readily positioned in or removed from the 15 ways.

A further object of the invention is to provide a store fixture comprising a cabinet combined with a novel means for securing the molding in place.

20 These objects and the several novel features of the invention are hereinafter more fully described and claimed and the preferred form of construction by which these objects are attained is shown in the accompanying drawings in which—

25 Fig. 1 is a perspective view of a store fixture embodying my invention.

Fig. 2 is an enlarged section taken on line 2—2 of Fig. 1.

30 Fig. 3 is an enlarged section taken on line 3—3 of Fig. 1.

Fig. 4 is an enlarged section taken on line 4—4 of Fig. 1.

Fig. 5 is a section through a different type of 35 fixture.

Fig. 6 is an enlarged section taken on line 6—6 of Fig. 5.

Fig. 7 is an enlarged section taken at the lower 40 left hand corner of Fig. 5.

Fig. 8 is an enlarged section taken at the lower right hand corner of Fig. 5.

The fixture comprises a base 1 having a rubber tile facing 2 on the forward face. Mounted on the base 1 is a horizontal frame member 3 and a 45 rear wall member 4 is provided having spaced frame members 5 connecting the horizontal member 3 with the upper horizontal member 6. The horizontal frame member 7 of the upper fixture section is positioned on the member 6 and a 50 double guide member 8 is secured to the member 7 by the screw 9 shown more particularly in Fig. 5. This double guide member is provided with a rib 10 and the member 6 is cut out at 11 to fit about this rib. A similar double guide member 55 12 is provided on the member 3 and is secured

in place by the screw 13 and a finish strip 14 is secured to the edge of the member 3 while a filler strip 15 is positioned between the member 14 and the double channel member 12. As shown in Figs. 2 and 7, a series of rollers 16 are provided 5 in the lower double channel member and are connected by side plates 17.

The door panels are inserted by inserting the rear panel 18 shown in Fig. 2 up into the double channel 8 and then fitting the lower edge of the 10 panel 18 into the channel 12 so that the door panel rests on the rollers 16. The other panel 19 shown in Fig. 4 is inserted in position in the same manner. These panels 18 and 19, as shown in Fig. 1, may be provided with hand grips 20 15 so that the panels may be moved longitudinally in the guide members. The outer edge of the horizontal member 7 extends beyond the edge of the member 6 and a trim member 21 is secured to this edge by the screw 22 shown in Figs. 20 2 and 4. A surface member 23 is positioned on the upper face of the member 7 and is provided with an upturned flange 24 at a distance from the edge. A double channel member 25 is secured to the member 7 by the screw 26 and engages 25 against the flange 24. This double channel member 25 is also provided with rollers 16 which are connected by side plates 17 and the sliding panels 27 and 28 are mounted on the rollers 16 in the double channel member 25 as shown more 30 particularly in Fig. 4. A horizontal partition 29 is provided above the member 7 and a double channel member 30 is secured to the lower face of the partition 29 as shown in Figs. 2 and 3 by means of the screw 31. A wide metal molding 35 member 32 is provided with a way 33 having undercut edges into which the rib 34 of the double channel member 30 fits and this rib 34 holds the molding member 32 in position against the outer edge of the partition 29.

40 This same construction is duplicated at the top of the store fixture in which a similar channel is attached to the horizontal top 35 and the molding 32 is secured in place in the manner shown in Fig. 3. On the upper side of the member 35 45 a series of short key members 36 are fitted into the channel 37 of the molding and the screws 38 extend through these key members 36 to hold them in place and thus hold the molding in place. Where an additional section is to be mounted 50 thereabove, a double channel member 39 is provided having a rib fitting into the channel 37 in the molding member 32 as shown in Fig. 2 and the sliding panels are fitted into the upper and lower double channel members as hereinbefore 55

described. Where the ends of the molding 32 come together between the sections of the fixture a connecting member 40 is provided which, as shown in Figs. 1 and 3, is secured to the molding 5 32 by the screws 41. This covers the ends of the molding and provides a neat appearance as will be understood from Fig. 1. The sliding panels may be of glass or laminated wood to slide in the double channels and are provided with hand 10 holds as shown for moving the panels horizontally.

In the form shown in Fig. 5, a base 42 is provided having a rubber tile facing 43 on the exterior. A bottom 44 is provided for this cabinet 15 which is also provided with glass walls 45 and a glass top 46. In this form, the double channels 47 and 48 are secured in position and the glass panels 49 and 50 are slidably mounted in these channels to roll on the rollers 16 provided in the 20 lower channels.

In this case, the sliding panels 49 and 50 are provided at the back of the cabinet and the trim molding 32 is secured to the member 44 by the keys 36 hereinbefore described which are secured to the member 44 and engage in the undercut channels 33 and 31 of the molding, as shown in Fig. 8. The glass wall 45, shown in Fig. 8, is provided in the pad strip 52 resting on the keys 36 and also supported by the wood strip 53. The 30 molding member 32 may also be provided with a packing strip 54 engaging the front face of the glass. The rear panels 49 and 50 are arranged to ride in the double channels and the double channel 55 at the end is provided with 35 rubber strips 56 against which the glass panels may strike when moved to the closed or extreme open position. By this arrangement it will be seen that different types of fixtures may be readily fabricated by the use of the double channels and molding to provide the best type of fixture for the place where it is to be used.

From the foregoing description it becomes evident that the device is very simple and efficient in operation, provides a combination from 45 which various structures may be fabricated and provides a device which accomplishes the objects described.

Having thus fully described my invention, its utility and mode of operation, what I claim and 50 desire to secure by Letters Patent of the United States is—

1. In a store fixture, a fixture member provided with a partition, a double channel member secured to each side of the partition adjacent 55 the edge, each double channel member being provided with an integral longitudinally extending rib on the exterior, a panel slidably mounted in each channel and a molding provided with channels for the ribs of the double channel mem-

bers, said molding channels being undercut at the edges and the ribs of the double channel members being shaped to fit said undercut channels, the arrangement being such that the ribs are inserted in the channels of the molding firmly 5 securing the said molding to said double channel members.

2. In a store fixture, a fixture member provided with a base, a partition and a top in parallel relation and in horizontal position, a member having a plurality of channels secured to the base, similar members secured to the upper and lower faces of the partition at its edge and a similar member secured to the lower face of the top at its edge, the channel members on the partition and the top each having a projecting rib, and a molding at the edge of the partition and another molding at the top having channels to receive the respective ribs, the channels of the molding having undercut edges and the said projecting ribs of the channel members fitting therein to prevent lateral displacement of the molding in relation to the channel members.

3. In a store fixture, the combination with a double channel member having a longitudinal rib extending outwardly therefrom at a right angle to the channels of said member, of a molding provided with a channel into which the rib is fitted, the arrangement being such that when the rib is fitted into the channel the molding member is firmly secured to and covers the outer face of the double channel member.

4. In a store fixture, a cabinet provided with at least one horizontal partition, a top and a base, moldings each provided with undercut channels in one face thereof and respectively secured to the front edges of the top and the partition, doors for the space between the partition and top and the space between the partition and base, and a plurality of channel members each provided with portions respectively fitting the said undercut channels of the molding on the top and the partition and providing horizontal channels for the edges of the respective doors.

5. In a store fixture of the cabinet type having a horizontal partition element, a molding for positioning at the front edge of the said horizontal partition and extending longitudinally of the cabinet, said molding having a pair of ways spaced a distance apart slightly greater than the thickness of the partition, means attached to the lower face of the partition at the forward edge engaging the lower way, and a similar means attached to the upper face of the partition at the forward edge engaging the upper way of the molding and sustaining the same in position.

HERBERT MALOTT.
